UNITED STATES PATENT OFFICE.

LESTER B. HOWELL, OF WILMINGTON, NORTH CAROLINA.

WATER-GLASS.

1,118,346.

Specification of Letters Patent.

Patented Nov. 24, 1914.

Application filed January 20, 1913. Serial No. 743,145.

To all whom it may concern:

Be it known that I, LESTER BRYANT HOWELL, a citizen of the United States, residing at Wilmington, in the county of New Hanover and State of North Carolina, have invented certain new and useful Improvements in Water-Glasses; and I do hereby declare the following to be a full, clear, and exact description of the invention, such as will enable others skilled in the art to which it appertains to make and use the same.

This invention relates to emergency valves as applied to boilers, and an object of the invention is to provide means for automatically injecting water into the boiler when the water in the boiler has reached a predetermined depth.

A further object of the invention is to equip the ordinary water gage of a boiler with means for automatically actuating an injector for the purpose of feeding water to the boiler.

With these and other objects in view, the invention consists in certain novel features of construction as hereinafter shown and described, and then specifically pointed out in the claims.

In the drawings, where similar reference characters designate corresponding parts: 30 Figure 1 is an end elevation of a locomotive boiler showing improvement connected thereto. Fig. 2 is an enlarged vertical central section through the water glass.

Corresponding and like parts are referred 35 to in the following description and indicated in the views of the drawings by the same reference characters.

Boiler explosions are frequently caused by the evaporation of all of the water in the 40 boiler, this condition resulting either from an oversight on the part of the attendant or from wilful neglect. Whatever the cause however, the almost invariable result of low water is an explosion, and to overcome this, 45 my invention aims to associate with the water glass a mechanism which will positively prevent the complete evaporation of water in the boiler. In accomplishing this result, I provide a glass having a float carried by the water in the glass, an injector or other steam-actuated means for forcing water into the boiler, and a valve actuated by the float and throwing the injector into operation.

50 Referring to the drawings, it will be seen that a boiler 1, which may be stationary, or

of locomotive type, has connected thereto a water gage 2. The lower end of this water gage is of the usual construction, having a water communication with the water of the boiler. The upper part of the gage is also formed as are ordinary water gages, but has added thereto a closure 3 secured to the glass of the gage and having therein a passage which may communicate by any suitable pipe 4 with the steam dome of the boiler. 55 Screwed upon the closure is a cap in the form of a hollow nut 5, the chamber 6 thereof communicating by means of a pipe 7 with a suitable cylinder 8. The closure 3 and the nut 5 are secured tightly together, and are provided with suitable packing for preventing the escape of steam. A float stem 9, the lower end of which is provided with a float 10, passes slidably through 75 openings 11 and 12 in the closure 3 and nut 5, respectively, the stem fitting tightly to prevent the escape of steam. Near the upper end of the stem 9, is provided a groove 13 of a length less than the distance between the top of nut 5, and the bottom of closure 3, but of greater length than the thickness of the closure. While this particular form of opening 13 has been shown, 80 it is to be understood that various other designs may be formed in the stem to accomplish the same result. The cylinder 8 has mounted therein, a piston 14, the piston rod of which is pivotally connected to one end of a pivoted link 15, while the other end 85 of the pivoted link 15 is connected in any suitable means to the handle of a steam injector 16. In the operation of this embodiment of the invention, it will be seen that when the water falls in the gage, the float 90 10, which does not necessarily fit steam-tight against the walls of the gage, will descend with the water until the lower end of the groove 13 passes below the lower surface of the closure. As soon as this last-described 95 condition takes place, steam will pass from the steam dome through the pipe 4 and passage, into the water gage, up through the groove 13 into the chamber 6 formed in the nut 5, and out through the pipe 7 to the 100 cylinder 8, the steam acting upon the piston 14 to force the same outwardly for the purpose of starting the injector 16. It is to be understood, of course, that I do not 105 limit myself to any fixed distance between the lower end of the groove 13, and the float, as this distance may be varied to suit 110

2
different conditions by any one of the well known adjusting means for valve rods. After the injector 16 has been set in operation, the same may continue until stopped 5 by the attendant, or by mechanism automatically operated by the rise of water in the boiler, this part of the mechanism forming no part of my invention. When the water rises within the gage the float will rise and 10 also the stem, and finally the groove 13 will establish communication between the chamber 6 and the upper end 25 of the housing which forms an exhaust for the steam behind the piston 14 so that the injector- 15 starter can return to its normal position as shown in Fig. 2. Thus it will be seen that as soon as the water reaches a predetermined 20 depth in the boiler, and water gage, the injector is set into operation for forcing water into the boiler.

By preference the water gages are surrounded by a suitable casing 24 which serves to protect the glass of the gage. If desired, a housing 25 can be erected upon the nut 5 25 for the protection of the upper end of the stem 9 to prevent the same from becoming bent through accident and thereby destroying the steam pipe fit which is necessary to the operation of this device. I have shown 30 no particular type of injector, insomuch as any of the approved forms can be used and I do not wish to be limited to the specific 35 means shown for starting the injector by means of a system of lever.

Having thus described the invention, what 35 I claim as new is:

1. In a device of the class described, the 40 combination with a gage having a closure

at its upper end provided with an opening 40 and with a passage communicating with the interior of the gage, and a pipe leading from said passage; of a float within the gage, a stem rising from the same through said opening and having a longitudinal groove 45 whose lower end is adapted to enter the gage 45 when the water therein falls, a cap screwed upon the closure and having an opening through which said stem passes, said cap also having an internal chamber, and a pipe leading from this chamber, for the purpose 50 set forth.

2. In a device of the class described, the combination with a gage having a closure at its upper end provided with an opening 55 and with a passage communicating with the interior of the gage, and a pipe leading from said passage; of a float within the gage, a stem rising from the same through said opening and having a longitudinal 60 groove whose lower end is adapted to enter the gage when the water therein falls, a cap nut 65 screwed upon the closure and having an opening through which said stem passes, the top of the nut being spaced from the closure so that as such stem rises the lower 70 end of its groove is closed by the closure before its upper end is opened by the cap, a pipe leading from the interior of the cap, and an exhaust mounted on the cap, for the purpose set forth.

In testimony whereof I affix my signature in presence of two witnesses.

LESTER B. HOWELL.
